UNITED STATES PATENT OFFICE

157,870

TABLE LIGHTER

George Bruce Kamp, Philadelphia, Pa., assignor
to Zippo Manufacturing Company, Bradford,
Pa., a corporation of Pennsylvania

Application February 10, 1949, Serial No. 772

Term of patent 3½ years

(Cl. D48—27)

To all whom it may concern:

Be it known that I, George Bruce Kamp, a citizen of the United States, residing at Philadelphia, in the county of Philadelphia and State of Pennsylvania, have invented a new, original, and ornamental Design for Table Lighter, of which the following is a specification, reference being had to the accompanying drawing, forming part thereof.

Fig. 1 is a perspective view of a table lighter, showing my new design; and Fig. 2 is a top plan view of the lighter shown in Fig. 1.

I claim:

The ornamental design for a table lighter, as shown.

G. BRUCE KAMP.
